UNITED STATES PATENT OFFICE.

GEORGE KRAKOWSKY, OF SOUTH BEND, INDIANA.

LOCOMOTIVE.

1,361,877.

Specification of Letters Patent. Patented Dec. 14, 1920.

Application filed July 6, 1920. Serial No. 394,238.

To all whom it may concern:

Be it known that I, GEORGE KRAKOWSKY, a citizen of the United States of America, residing at South Bend, in the county of 5 Saint Joseph and State of Indiana, have invented certain new and useful Improvements in Locomotives, of which the following is a specification.

The primary object of the present invention is the provision of a locomotive capable of attaining great speed from a minimum expenditure of fuel, the construction being simple and possessing great strength and endurance.

10 A further object of the invention is the provision of a high speed locomotive possessing great power after the nature of a double action compound engine, enlarged divers being employed whereby the draft 20 is equalized throughout the entire body of the locomotive.

A still further object of the invention is the provision of a locomotive having forward and rear drivers simultaneously operable by steam power derived from a double boiler having a single steam chamber and steam dome communicating with the steam chests of the driving cylinders.

Another object of the invention is the 30 provision of a locomotive having a central stabilizing truck assisting in maintaining the equilibrium of the locomotive in travel upon the track.

It is also designed to provide with a locomotive a tender having its truck connected for resiliently supporting the rear end of the locomotive cab for absorbing vibrations and jars incident to travel.

I also provide means upon my high speed 40 locomotive for slidably maintaining the same upon the track rails in case of the accidental derailment of the main drivers and whereby the locomotive will be maintained upright in a sliding position upon the track.

45 My double boiler construction is of the fire-tube type having dual fire boxes within the locomotive cab it being understood that either solid or fluid fuel may be employed according to the equipment of the railroad line.

With these general objects in view the invention consists of the novel combination and arrangement of parts hereinafter more fully described in connection with the accompanying drawings and in which like

reference characters designate corresponding parts throughout the several views.

In the drawings,

Figures 1, 2, and 3 are developed substantially continuous side elevational views of 60 my locomotive and tender, portions being omitted and broken away,

Fig. 4 is a vertical transverse sectional view substantially centrally through the locomotive with parts removed, 65

Fig. 5 is a similar sectional view through the double boiler at one point of connection between the boilers,

Fig. 6 is an elevational view of the central portion of the frame showing the swiv- 70 eled stabilizing truck,

Fig. 7 is a central longitudinal sectional view through the forward end of the locomotive,

Fig. 8 is a similar sectional view through 75 the central portion thereof,

Fig. 9 is a similar sectional view through the rear end of the double boiler and fire box, and

Fig. 10 is a detail view illustrating one of 80 the sliding shoes operatively positioned upon the track.

Referring more in detail to the drawings my invention broadly consists of a steam generator comprising upper and lower 85 boilers 10 and 11 arranged parallel one above the other with superposed fire boxes 10' and 11' respectively at the rear of the boilers and an outlet chamber 12 for the products of combustion at the forward end of the boilers having a smoke stack 13 at the top of the chamber. Similar side frames are secured opposite the side of the boilers 10 and 11 comprising central plates 14 with rear extensions 15 cut away longitudinally as 90 at 16 and also having forward extensions 17 with similar longitudinal cutaway portions 18.

The extensions 15 terminate in downward inclined portions 19 at the opposite sides of 100 the cab 20 at the rear of the boilers 10 and 11 with the fire box doors 21 and 22 positioned within the cab.

The forward extensions 17 terminate as at 21 adjacent the forward end of the boiler 105 connecting chamber 12 at the front of the locomotive.

The main driving cylinders 23 are oppositely positioned substantially centrally of the locomotive outwardly of the main frame 110

plates 14 and are operatively connected to steam chests 24 in the usual manner, the steam chests 24 being secured to the plates 14 beneath the cylinders 23. The boilers 10 and 11 being of the fire-tube type, the lower boiler 14 is provided with tubes 25 and the lower portion of the upper boilers 10 with similar tubes 26 opening at their rear ends in the fire boxes 11' and 10' respectively for conveying the heated gases and products of combustion through the said pipes to the chamber 12 into which the open forward ends of the tubes 25 and 26 are exhausted. The tubes 26 of the upper boilers 10 are provided in the lower portion thereof leaving a steam space 27 in the upper side of the top boiler 10 communicating with a steam dome 28 positioned substantially centrally upon the top of the boiler 10.

20 The main support for the locomotive comprises forward and rear drivers 29 and 30 respectively having main driving shafts 31 and 32 extending transversely through the space between the boilers 10 and 11 with the shaft 31 extending through the cutaway portions 18 of the forward extensions 17 and the rear shaft 32 through the cutaway portion 16 of the rear extensions 15 of the main frame. Main boxings 33 for the rear drive shaft 32 are connected by equalizing springs 34 and 35 with the rear frame extensions 15, the springs lying within the cutaway portions 16 of such extensions with their inner ends linked to saddle members 36 upon the boxes 33.

25 The rear ends of the rear springs 34 are connected by links 37 with the lower sides of the rear extensions 16 while the front end of the forward springs 35 are connected by links 38 with the upper sides of the rear extensions 16. In a similar manner, the forward drive shaft 31 is journaled in boxes 33' for supporting the forward extensions 17 of the main side frames by means of rear and forward springs 34' and 35' respectively. Each main cylinder 23 is double-acting having an axial piston rod 39 for driving front and rear cross heads 40 and 41 respectively slidably mounted in parallel guides 42 and 43 respectively extending forwardly and rearwardly from the main cylinders 23. The cross heads 40 and 41 are operatively connected to the hubs 44 and 45 of the front and rear drivers by means of main rods 46 pivoted between the cross heads and pins 47 eccentrically carried outwardly projecting from the hubs 44 and 45. The steam dome 28 is connected to the steam chests 24 by pipes 48 at the opposite sides of the locomotive, while link operating mechanism 49 of any well known form is operatively connected between the pins 47 and the valve stem 50 of the steam chest 24 outwardly of the ends of the steam chest and whereby the control of steam to the main cylinders 23 is

automatically accomplished during the operation of the locomotive.

An exhaust pipe 51 from each steam chest 24 empties into a manifold 52 between the boilers 10 and 11 extending forwardly to the chamber 12 with an angular pipe 53 projecting from the forward end of the manifold 52 upwardly into an ejector tube 54 through which the products of combustion from the chamber 12 pass to the stack 13 and whereby the exhaust steam through the pipe 53 entering the tube 54 accelerates the draft of the fire boxes 10' and 11'. A connecting conduit 55 between the boilers 10 and 11 is provided between each set of driving wheels 80 whereby the two boilers have a single steam space 27 in the upper boiler 10 with the lower boiler 11 normally filled with water as well as the conduits 55 and the upper boiler 10 to a point such as 56 above the level 85 of the fire tubes 26 therein. The usual form of air brake mechanism may be employed a pump 57 and brake cylinder 58 being herein illustrated to show a suitable position for the same upon one of the side plates 14 of the main frame.

20 A central equalizing truck 59 is positioned beneath the lower boiler 11 having relatively small wheels 59 for traveling upon the track and usual spring suspension means 61. A 95 socket 62 carried by the central truck 59 serves as a bearing for a ball 63 upon which rests a corresponding socket member 64 centrally secured to a connecting plate 65 spanning the lower edges of the side plates 14. 100 In this manner, the central truck 59 supports part of the weight of the locomotive being swiveled anti-frictionally mounted therebeneath by the supporting bearing 63. This arrangement stabilizes the locomotive 105 assisting in preventing the same from leaving the rails during excessive rates of speed and when rounding curves.

25 A wind-deflector 64 of suitable form is secured forwardly of the locomotive while a 110 slide member or shoe 65 at the bottom of the deflector and similar shoes 66 at the front and rear of the central truck 59 are normally positioned slightly above the track for slidable engagement therewith should 115 the drive or truck wheels accidentally leave the rails. A similar shoe 67 is carried beneath the cab 20 and it will be apparent that if the locomotive becomes derailed, the same would slide along over the rails upon the shoes 65, 66 and 67, without turning over. These shoes are of considerable width and suitably flanged as illustrated in the detail view Fig. 10, in connection with a rail 68 therein illustrated in vertical transverse 120 section. The throttle lever 69 is located within the cab 20 and operates in the usual manner.

30 A fuel carrier or tender 70 is coupled rearwardly of the cab 20 mounted upon its 130

- own truck 71. Means are provided for equalizing shocks and supporting a part of the weight of the cab 20 from the tender truck 71 and consists of an angular bar 72 coupled by a pin 73 with the bracket 74 of the shoe 67 beneath the cab 20. The bar 72 has its rear end anti-frictionally journaled by means of spaced balls 74' centrally of the truck 71 while the bar 72 extends through a bracket 75 depending from the rear end of the cab 20. The ball 76 in the bottom of the bracket 75 has the bar 72 mounted thereon while a ball 77 upon the top of the bar 72 has a spring 78 interposed between the same and an adjusting wedge 79 extending through the top of the bracket. The vertical vibrations of the cab 20 are absorbed by the springs 78 which is adjustable in tension by means of the wedge 79.
- 20 The complete operation of the invention will be fully understood from this detailed description thereof, the increased steam capacity of the two fire-tube boilers being apparent as well as the capacity for power possessed by the opposite double-acting main cylinders 23. The drive wheels 29 and 30 are preferably of greater diameter than the height of the boilers or cab 20 being capable of revolving by the great power of the steam plant. The locomotive is thoroughly equilibrated for maintaining the same upright on the track at great speeds of travel, the locomotive being capable of pulling great loads as well as traveling at unusually high speeds.
- 35 It will be noted that while the main cylinders 23 are carried outwardly of the side plates 14 of the main frame, the guides 43 for the cross heads 40 and 41 are outwardly of the driving wheels 29 and 30. The locomotive possesses great safety being prevented from leaving the track by the stabilizing central truck 59 and provided with the safety sliding means consisting of the shoes 65, 66 and 67 in the event of an accidental 45 derailment of the locomotive. The wind-deflector 64 forwardly of the locomotive decreases the air resistance during forward travel while the equalizing suspension springs 34, 35, 34' and 35' mount the boilers 50 and their mechanism in a cushioning manner upon the main shafts 31 and 32.
- While the form of the invention herein set forth is believed preferable it will be understood that minor changes may be made 55 therein without departing from the spirit and scope of the invention as claimed.
- Having thus described my invention, what I claim as new and desire to secure by Letters Patent is:-
- 60 1. A locomotive comprising a horizontal boiler, forward and rear drive wheels upon which the boiler is mounted, a main frame carried by the boilers, a central truck beneath the frame and central boiler and socket 65 connections between the truck and frame.
2. In combination with a locomotive and a tender truck, a bracket carried by the locomotive, a bar coupled beneath the locomotive and projecting rearwardly centrally beneath the truck, anti-friction connections between the truck and the rear end of the bar, a depending bracket upon the locomotive through which the bar extends, a shock-absorbing spring engaging said bar within the bracket and tension changing means for the spring carried by the bracket.
3. A locomotive comprising parallel boilers, a main frame having side portions secured to the opposite sides of the boilers, with cutaway portions corresponding to the space between the boilers, main shafts journaled through the cutaway portions of the frame, forward and rear driving wheels upon said shafts outwardly of the frame, spring equalizing suspension means between said shafts and the cutaway portions of the frame, driving means for the wheels carried by the frame outwardly of said wheels, a steam dome centrally of the upper boiler, steam pipes connected between said dome and driving means at opposite sides of the locomotive.
4. A locomotive comprising spaced superposed boilers, superposed fire boxes for the boilers rearwardly thereof, a cab at the rear of the fire boxes, main frame members at opposite sides of the boilers secured to the cab with cutaway portions corresponding to the space between the boilers, a main steam cylinder and steam chest carried by the frame at opposite sides of the boiler, steam connections between the upper boiler and said chests, forward and rear pairs of drivers adapted for supporting the boilers and operating means between the main cylinders and said drivers.
5. A locomotive comprising spaced superposed boilers, superposed fire boxes, for the boilers rearwardly thereof, a cab at the rear of the fire boxes, main frame members at opposite sides of the boilers secured to the cab with cutaway portions corresponding to the space between the boilers, a main steam cylinder and steam chest carried by the frame at opposite sides of the boiler, steam connections between the upper boiler and said chests, forward and rear pairs of drivers adapted for supporting the boilers, operating means between the main cylinders and said drivers, operative link connections between the steam chests and drivers, main shafts for the drivers transversely positioned between the boilers through the cutaway portions of the frames and equalizing spring mounting means between said shafts and the frames at the cutaway portions of the latter.
6. A locomotive comprising superposed boilers, a cab at the rear end thereof, a stabilizing truck centrally beneath said

boilers and a ball and socket support between said truck and boilers.

7. A locomotive comprising spaced superposed boilers, side frames carried by the
5 boilers, driving wheels upon which the frames are supported, a connecting member centrally beneath said frames, a stabilizing

truck beneath said connecting member and ball and socket connections between the truck and the connecting member of the 10 frame.

In testimony whereof I affix my signature.

GEORGE KRAKOWSKY.
